(57) **CLAIM**

The ornamental design for a squeeze-and-turn child resistant closure, as shown and described.

DESCRIPTION

FIG. 1 is a top perspective view of the squeeze-and-turn child resistant closure;

FIG. 2 is a top view of the squeeze-and-turn child resistant closure according to FIG. 1, the bottom of the closure being without ornamentation and forming no part of the claimed design;

FIG. 3 is a front or back view of the squeeze-and-turn child resistant closure according to FIG. 1, the two views being identical; and,

FIG. 4 is a left or right side view of the squeeze-and-turn child resistant closure according to FIG. 1, the two views being identical.
